UNITED STATES PATENT OFFICE.

JENNIE MILLER, OF AUSTIN, TEXAS.

DESIGN FOR A DISH-SCALDING DEVICE.

50,818.

Specification for Design.

Patented May 22, 1917.

Application filed March 31, 1917. Serial No. 159,040. Term of patent 14 years.

To all whom it may concern:

Be it known that I, JENNIE MILLER, a citizen of the United States, residing at Austin, in the county of Travis and State of Texas, have invented a new, original, and ornamental Design for a Dish-Scalding Device, of which the following is a specification, reference being had to the accompanying drawings, forming part thereof.

The figure is a perspective view of a dish scalding device, showing my new design.

I claim:

The ornamental design for a dish scalding device, as shown.

JENNIE MILLER.

Witnesses:

N. A. RECTOR,
J. W. MAXWELL.
